To all whom it may concern:

The design consists of a narrow border, 15 suggestive of a frame, with rectangular or straight-line sides and curved or rounded

corners. The field-center represents a marine view, with ships, and the immediate center is occupied with a portrait within oval lines, a flag in the rear thereof projecting 20 partly beyond the oval frame-line.

In testimony whereof I have hereunto af- 25 fixed my signature this 26th day of May, A. D. 1898.
